UNITED STATES PATENT OFFICE.

HERBERT HARDING PARMENTER, OF LONDON, ENGLAND.

PRINTING MACHINE.

Application filed October 14, 1924. Serial No. 743,617.

To all whom it may concern:

Be it known that I, HERBERT HARDING PARMENTER, a British subject, residing at 291 Croxted Road, Dulwich, London, S. E., 5 England, have invented certain new and useful Improvements in Printing Machines, of which the following is a specification.

This invention relates to printing machines more particularly intended for printing on continuous webs.

In connection with such machines it has already been proposed to mount the bed at the end of a pair of heavy rocking levers for an arcuate motion towards and away 15 from the platen, the inking rollers being pivotally mounted relatively to the rocking frame supporting the bed and making a single traverse between each impression.

In this construction the ink distributing 20 rollers are adapted to be continuously rotated in bearings carried by the frames holding the bed by means of an endless belt passing over idler pulleys, two of which required to be positioned coaxially with the axis of 25 the rocking frame. This construction involves several mechanical objections. For instance, the arcuate motion of the bed leaves a wedge-shaped space between the bed and platen at each lift necessitating a longer 30 stroke than will be required by a straight line movement, and the mechanical disadvantages arising in connection with the movement of the heavy bed at the end of long rocking arms operated by levers working at comparatively short leverage are 35 considerable. Further, the arrangement of the driving belt for the ink distributing rollers to follow the line of the rocking levers and pass round the axis about which they rock 40 is highly inefficient and the whole arrangement is liable to rapid wear and consequent prejudice to the quality of the work.

The present invention therefore has for its 45 object to combine inking rollers making a single traverse between each impression and continuously-rotating ink-distributing rollers with a bed having a straight line movement and remaining parallel to itself.

The invention further comprises improved 50 means whereby the ink distributing rollers, which rotate continuously in bearings carried by the reciprocating bed, are driven directly from a rotary shaft rotating in fixed bearings.

55 Further objects will be revealed in the accompanying description and set forth in the

following claims as will readily be understood.

The invention is illustrated in the accompanying drawings, in which

Fig. 1 is a front elevation of the press,

Figs. 2 and 3 are side elevations from the right and left respectively of Fig. 1,

Fig. 4 is a plan view of the inking mechanism on an enlarged scale.

Fig. 5 is a detail view of the gearing for the cam operating the inking rollers, and

Fig. 6 is a view of the gearing for operating a double press for printing two sides in one passage.

Referring now to the drawing, the platen 1, Fig. 1, is supported from corner pillars 2 by means of an inverted dove-tailed block 1^a from which it is removable by being moved endwise according to Figs. 2 and 3 75 rails 1^b being provided to take the weight through the intermediary of projecting pins 1^c. Yoke-shaped guides 1^d are provided for supporting the web immediately beneath the platen, the direction of movement of the web being laterally across the machine in the view indicated in Fig. 1. The type-carrying bed 3 is carried by a slide 3^b mounted to slide vertically in guides 3^a and reciprocated with a simple harmonic motion by a 80 crank 4 mounted on the main shaft 5 and engaging a cross-pin 5^a held in cheeks 5^b beneath the bed by means of a connecting rod 5^c. The length of the connecting-rod 5^c is adjustable to vary the pressure upon the 85 platen. The ink distributing drums 6 one each side of the bed 3 are carried by frames 7, 8, secured to the bed so that the drums 6 move up and down with the bed 3. The inking-rollers 9 are mounted on arms 10 pivoted at 11 in the frames 7 and 8. The arms 10 are oscillated to-and-fro by a cam-shaped slot in a disc 12 on the main shaft 5. A roll 13 on a slotted sliding arm 14 is connected to a lever 15, the other end of which carries 100 a pivoted link 16 fastened to the arm 10. The lever 15 rocks about a pivot fixed relatively to the pillars 2 of the machine frame, and the slot 14^a of the arm 14 is fitted with a sliding block 14^b mounted on the shaft 5 to guide its movement. The cam disc 12 is loose on the main shaft 5 and is driven from the shaft by a two to one reducing gearing 17, shown in plan in Fig. 5, so that the inking rollers 9 make only a single traverse 105 (forward or back) for each complete cycle of up and down movement of the bed 3.

110

The cam slot 12 is designed to maintain the speed of the rollers 9 across the type uniform during the movement of the bed 3.

The ink-distributing drums 6 are driven by a chain 18 passing over sprockets 19 on the drum spindles and guiding sprockets 19^a, and a sprocket 20 on a stub-shaft carried by the frame 7. A second sprocket 21 is mounted on this shaft and driven by a chain 22 passing around a sprocket 23 which is mounted eccentrically on the main shaft 5. By means of this eccentric sprocket the ink-distributing drums are rotated at uniform speed from the fixed shaft 5 whilst they are reciprocated vertically along with the bed 3 so as continually to approach and recede from the said shaft.

The inking-drums are preferably arranged to rotate in opposite directions so that the conditions under which the inking-rollers receive their charge of ink are exactly similar at each side of the machine, this being effected in the form shown by the provision of the double gears 19^b, 19^c, Fig. 2.

The ink duct 24 is carried by a duct frame 24^a, Fig. 4, mounted on a plate 24^e, adjustably mounted on lugs 24^b carried by brackets 24^c secured to two pillars 2, slots 24^d being provided in the plate 24^e to receive bolts 24^f to enable the position of the duct to be adjusted nearer to or further from the machine adjacent to one of the ink-distributing drums. The other ink-distributing drum is not provided with a duct but receives the surplus ink from the inking rollers after completing an impression and redistributes it upon them prior to their return movement. The roller 25 at the delivery end of the duct is rotated by a ratchet 26 and pawl 27 carried by a bell-crank 28 mounted on the roller spindle and rocked by connections 29, 30, 31, from an eccentric 32 on the main shaft 5. The ink-carrying roller 33, Fig. 3, is mounted in arms 34 mounted on a spindle 39 carried by the duct-frame and is reciprocated longitudinally by a lever 35, Fig. 4, pivoted at 36, and forked at one end 37 to engage a pin 38 on the spindle 39, and adapted to engage at the other end an inclined slotted arm 40 moving up and down with the bed 3. The roller 33 is moved horizontally between the roller 25 and the drum 6 at a certain part of the cycle by an arm 41 rigid with the spindle 39 operated by a spring-controlled stop 42, and the arrangement is such that the roller 33 is in position to touch the drum 6 when the bed is in the lower part of its range of movement. The spring-controlled stop 42 is carried by the rising and falling frame 8 and it will be seen that it engages the arm 41 on each downward movement of the frame so as to press the roller 33 against the drum 6 continuously until the frame 8 comes up again. As the stop ascends in its

return journey above the engaging point, the spring 42^a restores the stop 42, and the arm 41 is moved to restore the roller 33 to its position against the duct roller 25 by a spring 24^e secured to the plate 24^e, Fig. 4. By this arrangement, the shock of contact between the drum 6 and roller 33 is reduced to a minimum and the ink is evenly distributed, and any splashing is obviated.

A roller 33^a, Fig. 2, is provided at the other side of the machine to co-act with the second ink-distributing drum 6 and is reciprocated longitudinally whilst in contact with it to ensure even distribution of the ink upon it. For this purpose, the roller 33^a is mounted on arms 43 pivoted in bearing brackets 50 and controlled by a spring 51. The pivot spindle 52 carries collars 52^a engaging in slot 53 which is formed in an inclined wing 53^a of the frame 7 shown more clearly in Fig. 1.

In the form shown, the press is arranged to print a web passing through at right angles to the direction of traverse of the inking rollers. The web is fed forward intermittently, sufficiently to move the already printed material out of the range of the press and supply a clean section of the web ready to be printed.

The size of the press may be designed to print one, two or a large number of labels, tickets or the like at one time. If it is desired to print in two or more colours, the ink-duct 24 is divided by partitions 44 into the desired number of sections, and the ink-distributing drums are similarly divided; the feed is correspondingly reduced in proportion to the number of colours so that whilst one label or one series of labels is being printed in one colour, in one zone of the area of the platen, the others are being simultaneously printed in the other colours in adjoining zones by the same upward movement of a single type-carrying bed.

If it is desired to print the tags, labels, etc. on both sides in one passage through the machine, I use an arrangement similar in general plan to one that has been proposed for the printing of railway or other tickets. Thus, I use two presses of the kind already described arranged in tandem fashion, the second press being in close succession to the first and in opposite relation thereto, that is to say, with the platen below, and the reciprocating type-carrying bed descending upon it from above. Both presses are mounted on one supporting frame and are adjustable relatively to one another.

The individual presses for the tandem arrangement are identical with that described above, with cranks to reciprocate the beds and eccentric sprocket gearing to drive the ink-distributing drums. The two main shafts 5, 5^a, Fig. 6 are driven from a single source in their proper relation by a

shaft 60 at right angles to the direction of movement of the paper web between the two printing heads.

The lower main shaft 5 is driven directly by a worm 61 and worm wheel 62, and the upper one by an inclined shaft 63 and worm gearing 64. The worm gearing could be replaced by bevel gearing if desired.

It is to be understood that the various details of construction can be modified so long as the essential features of the invention, as outlined in the following claims, are maintained.

Further, in developing my invention, I have found that it can be applied to the printing of articles which are larger in size than post-cards and similar small articles. I, therefore, desire it to be understood that I can enlarge the platen and the form to any desired size, suitable for printing such articles as are usually printed on this class of machine, such as paper bags, leaflets, bill heads, memorandum forms, etc.

I claim:

1. In a printing machine, a frame, a platen supported thereby, a bed, a crank shaft mounted in the frame and connected to the bed for moving the bed vertically of the frame toward and away from the platen, frame plates movable with the bed, inking rollers mounted for pivotal movement on the frame plates, a disc mounted on the crank shaft, and means operated in the movement of said disc for moving the inking rollers across the bed during the movements of the bed relative to the platen.

2. In a printing machine, a frame, a platen supported thereby, a bed, a crank shaft mounted in the frame and connected to the bed for moving the bed vertically of the frame toward and away from the platen, frame plates movable with the bed, inking rollers mounted for pivotal movement on the frame plates, ink distributing rollers mounted on the frame plates, a fixed ink duct, an ink transferring roller operating between the duct and adjacent distributing roller, means for actuating the ink transferring roller, and means carried by the bed for longitudinally moving the ink distributing roller.

3. In a printing machine, a frame, a platen supported thereby, a bed, a crank shaft mounted in the frame and connected to the bed for moving the bed vertically of the frame toward and away from the platen, frame plates movable with the bed, inking rollers mounted for pivotal movement on the frame plates, ink distributing rollers mounted on the frame plates, a fixed ink duct, an ink transferring roller operating between the duct and adjacent distributing roller, a member supporting the ink transferring roller to permit operative movement thereof, and a spring controlled stop carried by one of the frame plates to engage and operate said member and thereby the transferring roller in the operation of the bed.

In testimony whereof I affix my signature.

HERBERT HARDING PARMENTER.
